UNITED STATES PATENT OFFICE.

RICHARD M. BEARD, OF NEW YORK, N. Y.

SECRET TELEPHONE-EXCHANGE.

1,117,156.

Specification of Letters Patent. Patented Nov. 17, 1914.

Application filed May 2, 1904, Serial No. 205,938. Renewed September 24, 1914. Serial No. 863,396.

To all whom it may concern:

Be it known that I, RICHARD M. BEARD, a citizen of the United States of America, and resident of New York, in the county of New York and State of New York, have invented certain new and useful Improvements in Secret Telephone-Exchanges, of which the following is a specification.

My invention relates generally to telephone systems, and specifically to a secret system of telephonic communication, whereby, in a central exchange instalment, when any two subscribers' lines are connected together in a circuit for talking, no central exchange operator or other party at the exchange is able through any manipulation of his telephone apparatus or switching devices to "listen in" or to connect any third subscriber in the said circuit, while the two subscribers are in communication. No complicated or unusual mechanism is needed in my system, privacy being secured through the disposition of the circuits.

My invention relates more particularly to a central exchange instalment employing a cordless switch board, such a switch board being commonly called a "desk monitor."

The object of a cordless switch board is to eliminate a serious and frequent trouble due to broken connections in flexible cords incidental to their use. However, the cordless switch board, on account of its limited capacity, is not adapted to large central exchanges, but is commonly used for private branch exchange work.

My present invention is of the same general character, and has the same underlying principles, as disclosed in my U. S. Letters Patent Number 767,038, issued August 9, 1904; the particular construction there described being applicable to the cord switch board—the more common of the two—while the details of the present construction apply more particularly to the cordless or desk monitor form of switch board. This later or present application contains the broader claims. Both the cord and cordless switchboards are sometimes used for practically the same work, namely, connecting together any two of a number of subscribers' lines; and both have operator's telephone circuits and listening keys for the operator.

In using the desk monitor board for private branch exchanges, the object is to give

the subscriber as many central office wires, 55 or trunks, as he requires, from one to three, and also to provide for seven extension instruments which may be located at various places about his offices. Any one of the extension instruments may be connected with 60 any one of the trunks, by the operator throwing the corresponding keys to connect both together, on any one of five different pairs of bus wires. It is also provided that the operator may connect any two of the extension instruments together, by operating the two keys respectively corresponding to connect them together on any one of the five buses. When two extensions are connected together, a common battery is supplied directly 70 to the bus wires by a feed from a main central exchange, but when an extension is connected with a trunk, no talking battery is, or need be, supplied at the monitor, for the battery is then supplied at the main central. 75

The construction thus far described is old, but is necessary to a proper understanding of my invention.

Generally, without regard to the exact scope, my invention consists of subscribers' 80 lines, trunk lines, switching keys and a group of wiring for connecting together any two subscribers' lines or for connecting any subscriber's line with a trunk line, and switching apparatus located at the exchange 85 instalment by which the exchange operator is prevented from having talking or listening connection simultaneously with any two connected subscribers.

In the prior art, listening keys are connected directly with pairs of bus wires, and with them, the monitor board operator may listen to any or all conversations at will, because he can listen in on any pair of bus wires connecting any two or more subscribers' lines. In my invention, each trunk line and each subscriber's line entering the exchange passes through corresponding individual listening keys, to each of which the operator's telephone circuit is multiplied, and mechanism is provided whereby when any listening key is thrown into listening position it is automatically maintained disconnected from the bus wires and at the same time the operator's circuit is 105 opened to every listening key occurring after it in the multiple. All of the other apparatus and circuits are arranged in the

manner usually employed in cordless exchange instalments.

For further explanation, reference will now be had to the accompanying drawings.

5 The desk monitor board there shown in diagram is of the regulation size, and so far as not necessarily modified by the addition of my invention, is of the regular design commonly employed wherever cordless 10 switchboards are used.

Figure 1 is a diagram showing my invention applied to a private branch exchange instalment using a cordless switch board. Fig. 2 is a diagram showing a portion of 15 what is shown in Fig. 1 on a greatly enlarged scale.

$E^1, E^2, E^3, E^4, E^5, E^6$ and E^7 each represent one side of respective subscribers' lines, or extensions, of which $E'^1, E'^2, E'^3, E'^4, 20 E'^5, E'^6$ and E'^7 represent the other sides respectively; and T^1, T^2, T^3 , and T'^1, T'^2, T'^3 , represent the opposite sides respectively of respective trunk lines, which may connect to another exchange like that illustrated, 25 or to a main central exchange.

$L^1, L^2, L^3, L^4, L^5, L^6, L^7, L^8, L^9$ and L^{10} are listening keys, in each of which one of the extension subscribers' lines or one of the trunk lines terminates respectively.

30 O is one side of the operator's telephone circuit and O' is the other side. The wires O and O' are connected respectively to opposite sides of the key L^1 , and the wire O' is connected to the next key L^2 through the 35 contacts 1 and 2, which are normally closed; the wires O, O' are connected respectively to opposite sides of the key L^2 , and the wire O is connected to the next succeeding key L^3 through the contacts 1^a and 2^a, which are 40 normally closed; and so on alternately, the manner of connecting the operator's telephone wires to the listening keys being to connect first one and then the other of them respectively to each succeeding key through 45 a normally closed pair of contacts on the preceding key in the multiple. The object in having the wires O and O' alternate with each other in passing through the normally closed contacts 1, 2 and 1^a, 2^a, and 50 so on, is that the operator's circuit may not be unbalanced by having the resistance of all these contacts on one side.

55 s^1 to s^{30} inclusive are double throw switch keys by means of which, with suitable wiring, any two subscribers' telephones may be connected together, or any subscriber's telephone may be connected with any one of the trunks.

60 $b^1, b'^1, b^2, b'^2, b^3, b'^3, b^4, b'^4$ and b^5, b'^5 are pairs of bus wires each pair of which multiples to one side of one of the double throw switch keys in each one of the series belonging to the respective extension lines, and each pair of which has included in series one side of one of the double throw

switch keys belonging to each of the trunks. The bus wires are connected as ordinarily to a common battery feed F, F' from the main central exchange, through corresponding retardation coils R . G and G' are the two sides of a generator circuit which multiplies to the first of each switch key in each series thereof belonging to the respective extensions, and which supplies the current for signaling on the extensions. the extra cam c , and the corresponding battery tap t, t' and retardation coil R' , are for supplying talking battery to the operator's circuit for talking locally, *i. e.*, with one of the extensions. The local battery supply will not be required when the operator talks out on the trunks, and may then be disconnected by operating the cam c .

Now let it be assumed that a party desires to call and talk with another party to which he has no direct line, but with whom he can get a connection through the exchange shown, and let us suppose that the party's line is the one of which the line $E^1 E'^1$ is the continuation, and proceed to trace the same. The wires E^1 and E'^1 respectively connect to the springs 3 and 4 of the listening key L^1 which springs are normally in contact with springs 5 and 6, from which wires connect each spring respectively to the springs 9 and 10 of the switch key s^1 . The springs 9 and 10 of the key s^1 are normally in contact respectively with springs 11 and 12, from which wires connect respectively to springs 13 and 14. Springs 13 and 14 are normally in contact respectively with springs 15 and 16, from which wires connect each spring respectively to s^2 , the next switch key in the series belonging to the line $E^1 E'^1$, and which has a similar arrangement of springs to the key s^1 , and which in turn is similarly connected by wires to s^3 , the remaining switch key in that series, the inside contact springs of which are connected up with a signal receiving device S . Thus it is seen that the three switch keys s^1, s^2 and s^3 are normally connected in series, through closed contacts thereon and on the listening key L^1 , with the line $E^1 E'^1$, and the switch keys s^4, s^5 and s^6 are similarly connected up with the line $E^2 E'^2$, and so on in like manner the corresponding switch keys are connected to each of the extension lines. The switch keys s^{22}, s^{23}, s^{24} , etc., however, for each trunk line, are connected thereto in multiple. When the operator receives the signal, he throws the listening key L^1 into the position to listen on the line $E^1 E'^1$, in which position the wedge w is forced in between the springs 3 and 4 far enough to cause them to break contact with the springs 5 and 6 and to make contact respectively with the springs 7 and 8. The springs 7 and 8 are tapped respectively to the wires O and O' , the two sides of the operator's

telephone circuit, and the operator is then in talking circuit with the party calling. As soon as the operator learns what subscriber the party calling wants to be connected with, he throws the switching key connected with the generator circuit and which corresponds with the number of the desired subscriber. Assuming that the call comes for the party having the line $E^2 E'^2$, to signal him, the 10 operator throws the switch key s^4 in position to signal on that line, in which position the wedge w^1 is forced in between the springs 9^a and 10^a far enough to cause them to break contact with springs 11^a and 12^a 15 and to make contact with springs 17^a and 18^a which are tapped respectively to G and G', the two sides of the circuit to the signaling generator, and then restores the key to the normal position. The operator may 20 now connect the two subscribers together for talking on any pair of bus wires not in use, as indicated by the busy signals B. If the pair of buses $b^1 b'^2$ is used, then the switch keys s^1 and s^4 are employed to make the connection. To do this, the wedge w^1 of the 25 key s^1 is forced in between the springs 13^a and 14^a far enough to cause them to break contact with springs 15^a and 16^a and to make contact respectively with springs 19^a and 20^a . The operator now 30 throws the listening key L^1 back to normal position, and the two parties are then connected together for talking. When they have finished, as indicated by the clearing out of the signal B when both receivers are 35 hung up, the switch keys s^1 and s^4 may be restored to normal position. A similar connection may be likewise established between any two of the lines on any pair of bus wires by operating two of the respectively 40 corresponding switch keys. If, after signaling, the operator desires to listen on line $E^2 E'^2$, he may do so by restoring the listening key L^1 to normal position and throwing the key L^2 into listening position in the same 45 manner that the key L^1 was operated. When the key l^2 is in position to listen on line $E^2 E'^2$ the wedge w' is forced in between the springs 3^a and 4^a far enough to cause them to break contact with the springs 5^a and 6^a 50 and to make contact with springs 7^a and 8^a , thus placing the operator's telephone wires O and O' in circuit respectively with E^2 and E'^2 , the two sides of the subscriber's line. The operator may listen upon any one of the 55 trunks in the same manner as upon an extension, and a trunk and an extension may be connected together for talking in the same way that two extensions are so connected. The wiring to the springs on the 60 switch keys belonging to the trunk lines is 65

such that when a trunk is connected to a bus wire (for talking on an extension) the common battery is disconnected therefrom, the trunks being fed by the battery at the main central exchange.

70

It will be seen that when any listening key is in position for the operator to listen on the corresponding line, the circuit therefrom to the switch keys which constitute the connecting means to the other lines, is broken. Furthermore, the method of wiring the operator's telephone circuit to the listening keys prevents the operator from connecting two subscribers together over his telephone circuit, by throwing two listening keys to listening position at the same time. For example, when the listening key L^1 is thrown into position to listen on the line E^1 and E'^1 , contact is broken between the springs 1 and 2, which are otherwise in contact, thus opening the wire O' to the key L^2 , and when the key L^2 is thrown into position to listen on the line $E^2 E'^2$, contact is broken between the springs 1^a and 2^a , which are otherwise in contact, thus opening the wire 80 O to the key L^3 . Similar springs are installed in the operator's circuit on every listening key, and by tracing the connections, as illustrated, it will be seen that when any key is thrown into listening position, one of the operator's telephone wires is opened to every key occurring after it in the multiple. It follows from the above that the operator can listen on but one line at a time.

85

90 My invention is shown and described in connection with certain well known telephone appliances, but other accessories may be made use of and the invention carried out in different ways without departing from the scope thereof as set forth in the claims. Those versed in the art will readily understand that many of the details of my system may be altered as conditions require in any special installation, absolute privacy to telephonic conversations being secured in any 95 case.

100

105 The reason that the lines have been shown in the accompanying drawings as terminating in the listening keys instead of in the signaling keys, which is usual, is to keep the novel features separate from that which is old. It is only necessary that each one of the lines passes through the corresponding listening key before it is connected to the connecting means, and it may be connected to and pass through the signaling key first without affecting the proper working of the listening key, as an inspection of the drawing will show.

110

115 I claim as my invention—

120 1. A telephone central exchange installation consisting of the combination of an operator's telephone circuit; means for detachably and electrically connecting together 125

130

- any two subscribers' lines; and devices adapted to be operated to connect the operator's telephone circuit to any one of the subscribers' lines, each of which devices, 5 when so operated, simultaneously disconnects both the said operator's circuit and the said subscriber's line from any other connections previously established, whereby the operator can listen on but one subscriber's line 10 at a time.
2. A telephone central exchange installation consisting of the combination of an operator's telephone circuit; means for detachably and electrically connecting together 15 any two subscribers' lines; and listening keys to each of which said operator's circuit is multiplied, and each key adapted, when in listening position, to open any one subscriber's line to all others, and to simultaneously connect the operator's telephone circuit to the said one subscriber's line, whereby the operator is unable to listen on any but the last named subscriber's line. 20
3. A telephone central exchange installation consisting of the combination of an operator's telephone circuit; means for detachably connecting together any two subscribers' lines; listening keys to each of which said operator's circuit is multiplied, 25 and adapted when in listening position to open any one subscriber's line to all others, and to simultaneously connect the operator's telephone circuit to the said one subscriber's line; and mechanism adapted when any 30 key is thrown into listening position to open one side of the operator's telephone circuit to every one of said listening keys occurring after it in the multiple. 35
4. A telephone central exchange installation consisting of the combination of an operator's telephone circuit; means for detachably connecting together any two subscribers' lines; listening keys to each of which said operator's circuit is multiplied, 40 and adapted when in listening position to open any one subscriber's line to all others, and to simultaneously connect the operator's telephone circuit to the said one subscriber's line; and a normally closed pair of contacts 45 on each of said listening keys and through which one of the wires to the operator's telephone is connected to the succeeding listening key in the multiple. 50
5. A telephone central exchange installation consisting of the combination of an operator's telephone circuit; means for detachably connecting together any two subscribers' lines; listening keys to each of which said operator's circuit is multiplied, 55 and adapted when in listening position to open any one subscriber's line to all others, and to simultaneously connect the operator's telephone circuit to the said one subscriber's line; a normally closed pair of contacts on 60 each of said listening keys and through which one of the wires to the operator's telephone is connected to the succeeding listening key in the multiple. 65
- which one of the wires to the operator's telephone is connected to the succeeding listening key in the multiple; and a device for opening said contacts whenever any said listening key is thrown to listening position. 70
6. A telephone central exchange installation consisting of the combination of an operator's telephone circuit; connecting means for detachably connecting together any two subscribers' lines; a listening key for each subscriber's line and to each of which said listening keys said operator's telephone circuit is multiplied, one pair of the terminals of each of said listening keys 75 being normally connected to a subscriber's line, one pair to said connecting means, and the remaining pair to the operator's telephone circuit. 80
7. A telephone central exchange installation consisting of the combination of an operator's telephone circuit; connecting means for detachably connecting together any two subscribers' lines; a listening key for each subscriber's line and to each of 85 which said listening keys said operator's telephone circuit is multiplied, one pair of the terminals of each of said listening keys being normally connected to a subscriber's line, one pair to said connecting means, and the remaining pair to the operator's telephone circuit; and a wedge for each listening key for controlling the connections of all of the said terminals thereof, and operating to connect the first named pair of terminals 90 with either the one pair or the other of the other two pairs. 95
8. A telephone central exchange installation consisting of the combination of an operator's telephone circuit; connecting means for detachably connecting together any two subscribers' lines; a listening key for each subscriber's line and to each of which said listening keys said operator's telephone circuit is multiplied, one pair of the terminals of each of said listening keys 100 being connected to a subscriber's line, one pair to said connecting means, and the remaining pair to the operator's telephone circuit; and mechanism adapted when any key 105 is thrown into listening position to open one side of the operator's telephone circuit to every one of said listening keys occurring after it in the multiple. 110
9. In a telephone system, means including devices controlled by the operator for establishing a plurality of talking circuits between different subscribers simultaneously, means operated when any device is actuated to connect the operator with a talking circuit, 115 for insuring the interruption of the operator's connection with all the other talking circuits, and means for additionally insuring the interruption of the operator's connection from any particular talking circuit which 120 125 130

can possibly be established at any time between the subscribers when such circuit is completed between two subscribers.

10. In a telephone system, means including operators' keys for establishing a plurality of talking circuits between different subscribers simultaneously, means operated when any key is displaced to connect the operator with a talking circuit, for insuring the interruption of the operator's connection with all the other talking circuits, and means for additionally insuring the interruption of the operator's connection from any particular talking circuit which can possibly be established at any time between the subscribers when such circuit is completed between two subscribers.

11. In a telephone central exchange instalment, the combination of subscribers' lines electrically connected together through the exchange, an operator's telephone circuit, and means adapted to be operated to connect said circuit to any one of said lines, which said means, when so operated, simultaneously disconnects said circuit and said any one of said lines from any other connections previously established.

12. In a telephone central exchange instalment, the combination of subscribers' lines electrically connected together through the exchange, an operator's telephone circuit, means adapted to be operated to connect said circuit to any one of said lines, and devices controlled by said means, which, when said means is so operated, simultaneously disconnect said circuit and said any one of said lines from any other connections previously established.

13. In a telephone central exchange instalment, the combination of subscribers' lines, an operator's telephone circuit, means for connecting together any two of said lines through the exchange of said instalment, a listening key for each said line, and contact springs governed by said listening keys for electrically connecting said circuit to either one of said lines but only while said one line is disconnected from all other lines.

14. In a telephone central exchange instalment, the combination of subscribers' lines electrically connected together through the exchange, an operator's telephone circuit, and listening keys adapted to be operated to connect said circuit to any one of said lines, which said listening keys, when so operated, simultaneously disconnect said circuit and said any one of said lines from any other connections previously established.

15. In a telephone central exchange instalment, the combination of subscribers' lines electrically connected together through the exchange, an operator's telephone circuit, listening keys adapted to be operated to connect said circuit to any one of said lines, and contact springs carried by said listening

keys which, when said listening keys are so operated, simultaneously disconnect said circuit and said any one of said lines from any other connections previously established.

16. In a telephone central exchange instalment, the combination of subscribers' lines electrically connected together through the exchange, an operator's telephone circuit, listening key wedges, and contact springs controlled by said listening key wedges, which, when said wedges are operated, simultaneously disconnect said circuit and said any one of said lines from any other connections previously established and connect said circuit to one of said lines.

17. In a telephone central exchange instalment, the combination of subscribers' lines, an operator's telephone circuit, listening keys for connecting any one of said lines to said circuit, and contact springs carried and controlled by said listening keys for invariably maintaining said circuit disconnected from all the remaining lines during the time that said any one line is connected to said circuit.

18. In a telephone system, means including operator's keys for establishing a plurality of talking circuits between different subscribers simultaneously, and means operated, when any key is displaced to connect the operator with a talking circuit, for insuring the interruption of the operator's connection with all the other talking circuits.

19. In a telephone central exchange instalment, the combination of subscribers' lines, an operator's circuit having contacts 1 and 2, and contact springs 3 and 4 for connecting said circuit to one of said lines for controlling the separation of contacts 1 and 2, and for simultaneously disconnecting said circuit from another subscriber's line.

20. In a telephone central exchange instalment, the combination of subscribers' lines, an operator's circuit, contact springs 3 and 4 for connecting said circuit to one of said lines, and for simultaneously disconnecting said circuit from another subscriber's line, contact springs 7 and 8 permanently connected to said circuit, and contact springs 5 and 6 adapted to be connected to said another subscriber's line, and normally in contact with the contact springs 3 and 4.

21. In a cordless telephone central exchange instalment, the combination of a listening key having a wedge, a subscriber's line spring contacts bearing thereon and movable thereby, an operator's circuit contacts in the path of the first named contacts, contacts 5 and 6 normally in contact with the first named contacts, and switching keys for connecting said contacts 5 and 6 with another subscriber's line.

22. In a telephone central exchange instalment, the combination of a listening key having a wedge, a subscriber's line spring contacts bearing thereon and movable thereby, an operator's circuit contacts in the path of the first named contacts, contacts 5 and 6 normally in contact with the first named contacts, switching keys for connecting said contacts 5 and 6 with another subscriber's line, and normally closed contacts 1 and 2 in series with the operator's circuit and controlled by the first named contacts. 70
23. In a telephone central exchange instalment, the combination of subscribers' lines, listening keys each having a pair of contacts normally open to the respective lines, and an operator's circuit to which said contacts are multiplied, said keys having spring contacts preventing said open contacts of any key from being connected to more than one of said subscribers' lines at a time. 75
24. In a telephone central exchange instalment, the combination of a subscriber's line, a listening key, a switching key, a second switching key, a second listening key, and a second subscriber's line, all in a closed electric series circuit, in the order named, and an operator's circuit, the contact springs of said listening keys being such that said series circuit is broken between said lines, upon actuating one of said listening keys to connect said operator's circuit to one of said lines. 80
25. In a telephone central exchange instalment, the combination of a subscriber's line, a listening key, a switching key, a second switching key, a second listening key, and a second subscriber's line, all in a closed electric series circuit, in the order named, and an operator's circuit, the contact springs of said listening keys being such that said series circuit is broken between said lines upon actuating one of said listening keys to connect said operator's circuit to one of said lines and that the said operator's circuit is broken between the two said listening keys should the two said listening keys be actuated. 85
26. In a cordless telephone central exchange instalment, the combination of subscribers' lines, an operator's circuit, switching keys connecting two of said lines electrically together, listening keys having contacts in a closed series circuit with said switching keys and also in series circuit with two of said lines, and other contacts for said listening keys, multiplied to said circuit and adapted to connect said circuit to one of said lines when a certain one listening key is out of the normal phase, the first contacts being disconnected. 90
27. In a telephone central exchange instalment, the combination of an operator's circuit, and listening keys, the wedge of 65
- any key, when operated for listening in making said key "dead" with respect to all the remaining keys. 95
28. In a telephone central exchange instalment, the combination of an operator's circuit, and keys normally connected together on one side of said circuit, and having means for preventing listening in upon more than one key at a time. 100
29. In a telephone central exchange instalment, the combination of listening keys, an operator's circuit multiplied to each of said listening keys, and means adapted, when any key is thrown into listening position, to open the said operator's circuit to every one of said listening keys occurring after it in the multiple. 105
30. In a telephone central exchange instalment, the combination of listening keys, an operator's circuit normally connected to said keys, and means automatically preventing more than one said listening key being connected to said circuit in listening phase at a time. 110
31. In a telephone central exchange instalment, the combination of listening keys, an operator's circuit multiplied to each of said keys, and means adapted, when any two said keys are thrown into listening phase at any one time, to automatically open the said operator's circuit between the two said keys. 115
32. In a telephone central exchange instalment, the combination of listening keys, an operator's circuit multiplied to each of said keys, and a normally closed pair of contacts on each of said listening keys and through which one side of the operator's circuit is connected to the next succeeding listening key in the multiple. 120
33. In a telephone central exchange instalment, the combination of listening keys, an operator's circuit multiplied to each of said keys, a normally closed pair of contacts on each of said listening keys and through which one side of the operator's circuit is connected to the next succeeding listening key in the multiple, and means operating to automatically open said contacts whenever any said listening key is thrown to listening position. 125
34. In a telephone central exchange instalment, the combination of subscribers' lines, a listening key for each subscriber's line, an operator's circuit multiplied to each of said keys, and means adapted, when any key is thrown into listening position, to open the said operator's circuit to every one of said listening keys occurring after it in the multiple. 130
35. In a telephone central exchange instalment, the combination of subscribers' lines, a listening key for each subscriber's line, an operator's circuit, and means operating automatically to prevent more than 135

one of said listening keys being connected in listening phase to said circuit at any one time.

36. In a telephone central exchange instalment, the combination of subscribers' lines, a listening key for each subscriber's line, an operator's circuit multiplied to each of said keys, and means adapted, when any two said keys are thrown into listening phase at any one time, to automatically open the said operator's circuit between the two said keys.

37. In a telephone central exchange instalment, the combination of subscribers' lines, a listening key for each subscriber's line, an operator's circuit multiplied to each of said keys, a normally closed pair of contacts on each of said listening keys and through which one side of the operator's circuit is connected to the next succeeding listening key in the multiple, and means operating to automatically open said contacts whenever any said listening key is thrown to listening position.

38. A telephone central exchange instalment consisting of the combination of an operator's telephone circuit; means for detachably and electrically connecting together any two subscribers' lines; and listening keys adapted, when in listening position to open any one subscriber's line to all others, and to simultaneously connect the operator's telephone circuit to the said one subscriber's line, whereby the operator is unable to listen on any but the last named subscriber's line.

39. In a telephone system, subscribers' lines, an operator's telephone circuit, and listening keys for connecting said operator's circuit to any one of said lines and for simultaneously disconnecting both said circuit and said one line from all other lines.

40. In a telephone central exchange instalment, an operator's telephone circuit, means connecting subscribers' lines together through the exchange in pairs, and devices, controlled by said means, which may at any time be operated simultaneously with said means to disconnect any pair of said lines from each other and to connect said operator's circuit with either the one or the other of the said any pair of said lines.

41. In a telephone system the combination of an operator's telephone circuit; means for electrically connecting together any two subscribers' lines, listening keys for each of said lines, said keys being adapted when in operative position to open any one subscriber's line to a plurality of the others, and to so connect the operator's telephone circuit that the operator is unable to listen on any but the line of the last mentioned subscriber.

In testimony whereof I have hereunto subscribed my name this thirtieth day of April, 1904.

RICHARD M. BEARD.
